INVENTOR

UNITED STATES PATENT OFFICE

148,055

DESIGN FOR A BICYCLE

Judson Craig Eubank, St. Augustine, Fla.

Application July 20, 1946, Serial No. 131,777

Term of patent 14 years

(Cl. D90—8)

To all whom it may concern:

Be it known that I, Judson Craig Eubank, a citizen of the United States, residing at St. Augustine, in the county of St. Johns and State of Florida, have invented a new, original, and ornamental Design for a Bicycle, of which the following is a specification, reference being had to the accompanying drawing, forming part thereof.

Fig. 1 is a side elevational view of a bicycle, showing my new design, and

Fig. 2 is a plan view thereof.

I claim:

The ornamental design for a bicycle, substantially as shown.

JUDSON CRAIG EUBANK.
